UNITED STATES PATENT OFFICE.

GEORGE W. HILL, OF NEW YORK, N. Y., ASSIGNOR TO AMERICAN TOBACCO COMPANY,
A CORPORATION OF NEW JERSEY.

CIGARETTE POUCH-PACKAGE.

1,344,635.

Specification of Letters Patent. Patented June 29, 1920.

Application filed August 4, 1916. Serial No. 113,092.

To all whom it may concern:

Be it known that I, GEORGE W. HILL, a citizen of the United States, residing at New York city, in the county of New York and State of New York, have invented certain new and useful Improvements in Cigarette Pouch-Packages, of which the following is a specification.

This invention relates to certain novel and useful improvements in cigarette packages. In the present invention it is my purpose to provide a cigarette package embracing among other features, a box-like casing adapted to have the cigarettes initially contained therein, preferably in a row, or rows, said casing being designed to be inserted within an outer cover of pouch-like construction, which is equipped with means capable of manipulation to bodily shift the casing outward through the mouth of the pouch to enable the individual cigarettes to be readily and conveniently removed from the casing.

It is also my purpose to provide a cigarette package of this character wherein the outer cover or pouch is preferably formed of a suitable fabric, or of a leather, such as pigskin or the like, which will present a neat and attractive appearance, and which will be retained by the purchaser for future use, instead of being discarded, as is commonly done in the case of ordinary cigarette boxes or containers.

Furthermore, I propose to provide a cigarette package wherein the box-like casing in which the cigarettes are initially packed, is provided with a bendable or removable flap which may be manipulated or broken down to expose the adjacent ends of the cigarettes, thereby enabling the latter to be more readily removed, said bendable flap, when the casing is arranged within the pouch, corresponding to a similarly located flap forming a part of the front wall of the pouch whereby both of the flaps may be simultaneously bent outward to enable a person to have access to the cigarettes.

Another object of the invention is the provision of a cigarette package wherein the cigarettes will be protected against breakage due to exterior pressure, and furthermore, such cigarettes will also be protected against atmospheric influences and the entrance of dust, dirt and other for-

ign substances which might tend to injure or destroy such cigarettes.

I also aim to provide a package which will embody the desired features of simplicity, attractiveness and convenience.

With the above recited objects, and others of a similar nature in view, my invention consists in the construction, combination and arrangement of parts set forth and falling within the scope of the appended claims.

In the accompanying drawings,

Figure 1 is a perspective view of the pouch member of my improved package.

Fig. 2 is a similar view showing the cigarette-containing casing properly inserted within the pouch member.

Fig. 3 is a perspective view of the casing removed from the pouch.

Fig. 4 is a perspective view of the complete and closed package.

Fig. 5 is a perspective view of a modified form of pouch member.

Referring now to the accompanying drawings, in detail.

A indicates the inner casing or container in which the cigarettes are initially packed, preferably in a row or rows, such cigarettes being shown as C. The outer cover, which is in the nature of a pouch or pocket, is indicated as an entirety by the letter B. The casing or container A is preferably in the nature of a box-like member which may be made from a blank of card-board, box-board or other suitable relatively stiff material, this box including the bottom wall 1, the end walls 2, the rear wall 3 and the front wall 4. This latter is preferably scored along the line 5 to provide a flap 6, which may be bent or folded outward, or if desired may be completely severed from the front wall to expose the upper ends of the cigarettes C, thereby enabling the latter to be more readily and easily grasped and removed as occasionally required. This box-like casing or container A is adapted to be received by, and contained within the pouch or pocket B which is best shown in detail in Fig. 1.

When a purchaser receives a package of cigarettes from a merchant, such package may embody the casing A filled with the cigarettes and contained within the pouch or pocket B, and after the cigarettes of such

package have been consumed, the casing A may be discarded. However, it is not intended that the pouch or pocket, B, be thrown away by the person, but on the contrary the purpose is to have this pouch or pocket constitute a permanent possession for the consumer, inasmuch as other casings A containing cigarettes may be placed therein from time to time.

10 Further, I prefer to make this pouch of fabric, of leather, or of other pliable, durable material, pigskin being particularly adapted for this purpose.

This pocket or pouch B comprises a bottom wall 7, a rear wall 8, and a front wall 9 and side walls 10, and with the side walls uniting the front and bottom walls along the stitched seams 11, and thereby giving to the package a permanent box-like shape. This 20 pocket or box is further provided with a relatively wide top or closure flap 12, preferably formed integral with the rear wall 8 carrying a socket member 13 adapted to coöperate with a ball stud 14 carried by the front wall 9, the socket and ball stud forming 25 an ordinary snap fastener.

In order to draw, or partially draw the cigarette-containing casing A out through the mouth 15 of the pouch or pocket and thereby expose the casing with the cigarettes, as shown in Fig. 2, so that the individual cigarettes may be conveniently removed, I attach to the inner face of the rear wall 8 of the pocket as at 16, one end of a strap or ribbon 17, and the said ribbon being looped downwardly as at 18 and then reeved through slot 19 in the front wall of the pouch or pocket, the free end of the strap or ribbon being exposed at the outside of 40 the pouch or pocket and at its terminal provided with a tab 20 forming a finger grip for enabling the ribbon to be more easily manipulated to shift the contained casing A with the cigarettes. A reinforcing strap 45 21 is located at the outer face of the pouch or pocket adjacent to the slot and forms a guide or bearing over which the ribbon may run.

When preparing the package for the market, the cigarettes are packed in the casing or container A, and the latter is placed in the pouch or pocket which may be closed as shown in Fig. 5. When it is desired to have access to the cigarettes in order to remove 50 one or more of the same, it is only necessary to open the flap, 12, and then grasp the tab 20 of the strap or ribbon 17 and pull upward on the same, and inasmuch as the bottom portion of the casing A rests in the 55 loop 18 of the ribbon or strap 17, the upward pull on the strap will result in elevating the casing A and projecting the upper portion of the latter through the mouth of the pouch or pocket as shown in Fig. 2. The 60 flap 6 of the casing A may then be bent out- 65

ward and downward and a cigarette or cigarettes removed. The casing A containing the remaining cigarettes may then be shifted downward or back into the pouch or pocket, and this movement will result in restoring the ribbon or strap to its original position ready to be manipulated to again elevate the casing when necessary.

In Fig. 5 I have shown a slightly modified form of outer pouch or pocket. In this case 75 the looped strap or ribbon is omitted, and the front wall 9' is partially cut away from its top edge down as shown adjacent to both side edges as shown at 22 to provide a flap 23, which may be folded downward and 80 upward along the crease or score 24. It will be noted that this flap 23 corresponds somewhat to the flap 6 of the cigarette-container casing A, so that when the casing is arranged within the pouch or pocket, the 85 two flaps will lie in juxtaposition.

Consequently, when the person wishes to have access to the cigarettes within the casing, it is only necessary to open back the flap 12' of the pouch or pocket and grasp both 90 the flaps 6 and 23 simultaneously bending the same downward and thereby exposing the top ends of the cigarettes.

From the above description taken in connection with the accompanying drawings, 95 the manner of packaging the cigarettes and of using the package will be readily understood. It will be seen that the arrangement is such that ready and convenient access may be had to the cigarettes within the 100 package, and at the same time when the package is closed, such cigarettes are preserved from the deleterious influences of atmospheric changes, and against the entry of all foreign substances which might tend 105 to injure the same.

Furthermore, the outer pouch or pocket forms a neat, attractive article, especially when made of leather, such as pigskin or the like, and is such that it will be not discarded after the cigarettes originally contained therein have been used, but will be preserved for future and successive use.

While I have herein shown and described the preferred embodiment of the invention, 115 I wish it to be understood that I do not confine myself to all the precise details of construction herein set forth by way of illustration, as modification and variation may be made without departing from the spirit 120 of the invention or exceeding the scope of the appended claims.

What I claim is—

1. A cigarette package comprising a box-like casing of relatively stiff material and in 125 which the cigarettes are initially packed, said casing having a permanently open top portion, and a bendable front wall portion adjacent the open top portion, and a flexible pouch in which the casing is slidably received 130

and removably contained, such pouch having a body portion conforming to the shape of the casing and having a flexible closure flap connected with the top portion of one wall and adapted to overlie the open top portion of the casing and to lie flat against that wall of the pouch opposite to the wall with which it is connected, and means associated with the pouch and operable from outside the front wall of the latter for moving the casing partially outward through the top end or mouth of the pouch to expose the cigarettes within the casing, said means being concealed when the flap is closed.

2. A cigarette package comprising a box-like casing of relatively stiff material adapted to initially have a row of cigarettes, and the said casing having an open end portion and the front wall provided with a bendable flap to expose the top end portions of the cigarettes, and a flexible box-like pouch corresponding in shape to the shape of the casing and adapted to receive and contain the latter and its cigarettes, said pouch having a cover flap, and a strap attached at one end of the inner rear wall of the pouch and having its intermediate portion constituting a loop, the outer free end portion of such strap extending through a slot in the wall of the pouch to the outside of the latter and normally lying beneath the cover flap while the latter is closed, such strap being adapted to receive the lower portion of the casing and to move said casing outward partially

through the mouth of the pouch when the loop of the strap is shortened by pulling on the exposed end thereof.

3. A cigarette package comprising a box-like casing of relatively stiff material adapted to initially contain and protect the cigarettes, having an open end portion the front wall of which is made bendable at a point below the top end portions of the cigarettes so that the latter may be easily grasped for removal, a pouch composed entirely of flexible material having its lower end closed and its upper end open, adapted to slidably receive and removably contain the casing and its cigarettes, a strap fastened at one end to the inner face of one of the walls of the pouch and extending beneath and wrapped about the lower end portion of the contained casing, the free end of said strap extending through a slot formed in the opposite wall of the pouch from that to which the strap is fastened, and a closure flap extending from one vertical wall of the pouch and adapted when in closed position to overlie the open end of the pouch, to extend beyond the bendable portion of the front wall thereof and to be fastened thereto.

In testimony whereof I affix my signature in the presence of two witnesses.

GEORGE W. HILL.
